UNITED STATES PATENT OFFICE

99,278

DESIGN FOR A SHOE

Bernard R. Goldman, Cincinnati, Ohio, assignor to The Feder-Gregg Shoe Company, Inc., Cincinnati, Ohio, a corporation of Ohio

Application December 20, 1935, Serial No. 60,201

Term of patent 3½ years

To all whom it may concern:

Be it known that I, Bernard R. Goldman, a citizen of the United States of America, residing at Cincinnati, in the county of Hamilton and State of Ohio, have invented a new, original, and ornamental Design for a Shoe, of which the following is a specification, reference being had to the accompanying drawing forming part thereof.

In the drawing,

Fig. 1 is a front, perspective view of a shoe showing my new design; and

Fig. 2 is a rear, perspective view of the shoe shown in Fig. 1, the vamp cover element being slightly lifted to show the arrangement of the lacing therebeneath.

I claim:

The ornamental design for a shoe, substantially as shown and described.

BERNARD R. GOLDMAN.
